NELLIE DICKEY, OF SNYDER, NEBRASKA.

DOOR LATCH.

Application filed March 23, 1927. Serial No. 177,651.

The invention relates to door latches, and has for its object to provide in combination with a hinged door latching device an arcuate member concentric with the hinging point of 5 the door and having notches with which a slideable bar controlled by the latch operating mechanism cooperates for holding the door in open positions.

A further object is to provide a bell crank 10 lever connection mounted on the door, to one arm of which the latching bar is pivotally connected and a link connection between said bell crank lever and the pivoted latch, whereby upon raising said latch to open position, 15 the slideable bar will be moved out of engagement with the notches of the arcuate member for allowing the door to be opened.

A further object is to provide spring means 20 for normally forcing the latching bar upwardly towards the arcuate member.

With the above and other objects in view the invention resides in the combination and arrangement of parts as hereinafter set forth, shown in the drawing, described and claimed, 25 it being understood that changes in the precise embodiment of the invention may be made within the scope of what is claimed without departing from the spirit of the invention.

In the drawing:—

30 Figure 1 is a view in elevation of the door showing the same in closed position.

Figure 2 is a detail sectional view taken on line 2—2 of Figure 1.

Figure 3 is a bottom plan view of the arcuate member.

Figure 4 is a detail sectional view taken on line 4—4 of Figure 1.

Referring to the drawing the numeral 1 designates the door which is hingedly mounted 40 at 2 within a door frame 3. Secured to opposite sides of the door 1 adjacent its free end by means of rivets 4 are plates 5 in a sleeve 6 of one of which plates is rotatably mounted a shaft 7, which shaft has its ends provided 45 with handle members 8 on opposite sides of the door whereby the mechanism hereinafter set forth, may be controlled from either side of the door. Shaft 7 is provided with a latching arm 9, which latching arm pivotally moved in a vertical plane and is adapted to engage over the keeper 10 for holding the door 1 in closed position. Pivotally connected at 50 11 to the outer side of the door is a bell crank

lever 12, to the arm 13 of which is pivotally connected at 14 a link 15, and which link is 55 in turn pivotally connected at 16 to the latching arm 9, therefore it will be seen that when the operator rotates the shaft 7 for raising the latching arm 9, the link 15 will rock the bell crank lever 12 on its pivotal point thereby moving the arm 17 of the bell crank lever downwardly and imparting a pull downwardly on the vertically slideable bar 18, which bar is pivotally connected at 19 to the arm 17. The bar 18 is slidably mounted in 60 bearing members 20 carried by the face of the door and terminates above the upper end of the door, where its end will be received in any of the notches 21 in the under side of the arcuate door holder 22, which door holder 65 is concentric with the hinging points 2 of the door, consequently the door may be held in various opened positions, and the use of conventional forms of door stops is obviated. The arcuate member 22 is provided with an 70 upwardly and inwardly extending brace 23, which is connected at 24 to the frame of the door and the ends of the arcuate member are connected at 25 to the frame, therefore it will be seen that the arcuate member is thoroughly 75 braced at all times.

Disposed within a chamber 26 of the door 1 and connected at 27 to a post carried by the slideable bar 18 is a coiled spring 19, which cooperates with the slideable bar and a fixed 80 support for normally forcing the slideable bar 18 upwardly and against the contractile force of which the operator moves the mechanism hereinbefore set forth during an unlatching operation.

From the above it will be seen that a combined door latching and door holding mechanism is provided which will positively hold the door in closed position at all times, and will also hold the door in various opened positions, thereby preventing slamming of the door and obviating the use of conventional forms of door stops as at present in use.

The invention having been set forth what is claimed as new and useful is:—

The combination with a hinged door, a pivoted latch carried by said door, a handle member carried by said latch, an arcuate notched member above the door concentric with the hinging point thereof, a vertically slideable 105 bar carried by the door and cooperating with

the notches of the arcuate member for holding the door in various opened positions, a bell crank lever, said slidale bar being pivotally connected to one of the arms of the bell crank lever and a link connection between the other arm of the bell crank lever and the pivoted latch and curving over the handle member and forming means whereby when said latch

is pivotally moved upwardly said bar will be moved downwardly to unlatched position and spring means for normally forcing said slideable bar upwardly. ¹⁰

In testimony whereof I hereunto affix my signature.

NELLIE DICKEY.
